ADJUSTABLE CUTTER FOR BORING-BARS AND THE LIKE.

1,140,261.

Specification for Design.

Patented May 18, 1915.

Application filed December 16, 1913. Serial No. 806,956.

To all whom it may concern:

Be it known that I, THOMAS EDWARD PATTINSON, a subject of the King of Great Britain, residing in Walthamstow, London, England, have invented certain new and useful Improvements in Adjustable Cutters for Boring-Bars and the like, of which the following is a specification.

This invention relates to double ended cutters for use with engineers' boring bars. As hitherto constructed when cutters of this class become worn it is necessary in order to restore them to their full length that they should be heated and then drawn out to the desired extent. This method of procedure occupies considerable time in view of the numerous operations involved, and further necessitates the retempering of the tool.

The present invention has for its object to produce a double ended cutter for a boring bar which cutter is so constructed that the necessary elongation thereof may be effected without the aid of heat. With a cutter according to the present invention, moreover, provision may be made whereby the degree of the expansion may be controlled so that cutters of predetermined length may be readily produced.

A cutter according to the present invention comprises two hard steel cutting bodies which are connected by a piece or length of some metal which is of a sufficiently ductile character to elongate under pressure, which pressure may conveniently be produced by hammering.

In order to produce cutters of any predetermined length, the cutter is placed in a frame or box, the distance between the end walls of which is equal to the desired length of the cutter. The yielding metal center is then hammered until further elongation is checked by the end walls of said frame or box.

In order that the invention may be the better understood, drawings are appended in which:—

Figure 1. is a side elevation of a cutter constructed in accordance with this invention. Fig. 2. is a plan. Fig. 3. is a side elevation showing the cutter with the expandible metal center omitted. Fig. 4. is a plan of the parts shown in Fig. 3. Fig. 5. is a side view partly in section showing the tool for expanding the center of the cutter in position. Fig. 6. is a side elevation showing

a cutter after repeatedly expanding the center portion. Fig. 7. is an elevation partly in section showing the cutter in the box for limiting the expansion of the center portion and with the tool in position ready to expand the center. Fig. 8. is a plan showing the tool in the box ready for the application of the expansible center portion. Fig. 9. is a side elevation of the parts shown in Fig. 8. Fig. 10. is a plan showing the cutter in position in the boring bar. Fig. 11. is a side view of the tool employed to effect the expansion of the center part of the cutter.

Referring to the accompanying drawings, *a* and *b* indicate the respective cutting ends 70 of the tool and which ends as shown are provided at *c* with cutting edges. The parts *a* and *b* as shown in the drawings are recessed at *a*¹ *b*¹, such recess forming a key to retain the ends of the expansible metal center portion *d*. The opposite edges of the center portion *d* are preferably of angular outline, for example, V shaped, as shown at *a*² *b*² Figs. 1, 5, 6, 7, and 9.

While I do not desire to limit myself to any precise method of assembling the parts of the cutter, from my own experience I find in practice that this may most conveniently and rapidly be effected with the aid of the device shown in Figs. 8. and 9. 85 In the figures referred to, there is shown a trough or box comprising a bottom *e*¹ side walls *e*² and an end wall *e*³. Formed at suitable distances apart along the bottom *e*¹ of the box are holes *e*⁴ adapted to receive 90 pegs Figs. 8 and 9, formed at the lower end of a plate *e*⁵ which plate is of substantially the same width as the space between the side walls *e*². The parts *a* and *b* are placed in position in the box, the part *a* being placed 95 with its outer end in contact with the end wall of the box, while the outer end of the part *b* abuts against the plate Fig. 9. Molten metal is then poured in until the space left between the inner ends of parts 100 *a* and *b* is filled as also the recesses *a*¹ and *b*¹ in said parts. The space between the side walls of the box is substantially equal to the width of the cutter. It will be understood that the parts *a* and *b* will be tempered before being placed in position and connected by the molten metal.

While I do not desire to limit myself in any way to the employment of any particular metal or alloy of metals for the center 105 110

part of the cutter, I have found in practice that it is preferable to use a quick cooling metal, such for example, as hard tinman's solder. The surfaces contacting with the 5 solder are first tinned to secure proper cohesion of the solder with the tool.

Obviously instead of solder as above described, I may employ any metal which as compared with the end parts *a* and *b* is of 10 a nature such that it will, when hammered or otherwise subjected to pressure, be caused to elongate. Thus, for example, I may form the part *d* of brass, copper, iron, mild steel.

15 Instead of melting the metal, the center portion may be fitted to the ends *a* and *b* and secured therein by expanding the parts engaging the recesses *a*¹ *b*¹.

There are other methods of attaching the 20 center part *d* to parts *a* and *b* which will readily be apparent to those skilled in the art and which consequently need not be here further specified.

When it is desired to elongate the cutter, 25 the soft center portion *d* is subjected to pressure which may most conveniently be effected by hammering the same. In order that the hammer blows may be more effective, I prefer to employ a device such as *f* 30 shown in elevation in Fig. 11 and which device is preferably formed of round metal and is of substantially U shaped outline. In use the limbs of the device are caused to straddle the center *d* and the cutter is placed 35 upon some hard surface when the upper member of device *e* is hammered, the pressure thus applied causing the part *d* to expand. The extent to which the expansion of part *d* may be carried is limited only by 40 the thickness of said part *d*. In Fig. 6. I have illustrated the appearance of a cutter after repeated expansion of the part *d* which it will be noted is reduced from its original 45 thickness to a narrow web *d*¹ in which condition the cutter is still serviceable, as the repeated hammering has hardened the part *d*¹ so that it is still sufficiently strong for use.

As will be readily understood, it is desirable 50 in some cases that the expansion of the center part *d* shall be controlled as upon the one hand it is difficult to regulate the force of the blows of the hammer so that the desired expansion is not exceeded, while upon the 55 other hand, it is troublesome to repeatedly examine the cutter by means of calipers or other gage in order to see when the cutter reaches the desired length. In order, there-

fore, to overcome the difficulties above stated, I employ a box or frame such as shown in 60 Fig. 7 and which is provided with side walls *g*, ends *g*¹ and a bottom *g*². The distance between the ends *g*¹ is equal to the extreme 65 overall dimensions of the cutter. The bottom of the box as also the upper edges of 70 the side walls are recessed as shown at *g*³ to permit the application of the aforesaid body *f*. The part *d* under the blows of the hammer will expand until the ends of the cutter 75 press against the ends *g*¹ of the box when further elongation of the cutter will be prevented.

In Fig. 10. the cutter is shown as in position in the boring bar, indicated by *h*, and which is provided with a slot which, while being of substantially the same depth as the height or thickness of the cutter is of somewhat greater width so that there is left upon one side a sufficient space to permit the introduction of a spring *h*¹ or any other suitable device. It will be noted that the bar is of sufficient diameter to prevent either of the ends of the soft metal center *d* being exposed so that no strain falls upon this portion. The position of the spring *h*¹ is upon 85 the side of the cutter facing the direction of the feed which in Fig. 10 is shown by the arrow *i*.

Claims:

1. A double ended cutter for a boring bar 90 comprising two cutting members and an intermediate member of softer extensible metal attached at each end to one of the cutting members.
2. A double ended cutter for a boring 95 bar, comprising two cutting members of hard steel, the ends thereof being recessed, an intermediate member of softer metal, projections on the ends of said intermediate member engaging said recesses in the ends of 100 the cutting members.
3. A double ended cutter for a boring bar, comprising two cutting members of hard steel, the ends thereof being recessed, an intermediate member of solder, projections upon 105 the ends of said intermediate member engaging said recesses in the ends of the cutting members.

In witness whereof I have hereunto signed my name in the presence of the two 110 undersigned witnesses.

THOMAS EDWARD PATTINSON.
